United States Patent Office

Des. 204,832
Patented May 17, 1966

204,832

PHOTOGRAPHIC PRINT PROCESSOR

Ralph M. Vigna, Rochester, N.Y., assignor to Eastman
Kodak Company, Rochester, N.Y., a corporation of
New Jersey

Filed Feb. 24, 1965, Ser. No. 83,952

Term of patent 14 years

(Cl. D61—1)

FIG. 1

FIG. 2

FIGURE 1 is a front perspective view of a photographic print processor showing my new design; and

FIGURE 2 is a perspective view taken from the rear thereof.

I claim:

The ornamental design for a photographic print processor, as shown.
